SPRING ASSEMBLY

George A. Stackhouse, Oakland, Calif., assignor to
L. A. Young Spring & Wire Corporation, De-
troit, Mich.

Application January 3, 1939, Serial No. 248,990

10 Claims.

(Cl. 5—260)

This invention relates to improvements in spring assembly.

The main objects of this invention are:

First, to provide an improved spring assembly for mattress cushions and the like which is effective in holding the sides of the spring assembly in desired position without the employment of transverse braces.

Second, to provide a spring assembly for upholstered structures in which the border springs may yield under load or stress but are promptly returned to initial position when the distorting load is removed.

Third, to provide a spring filler or assembly for mattresses and the like which has in effect a stiffened edge or border and at the same time one which may yield without permitting distortion.

Fourth, to provide a spring assembly for mattresses and the like which is not likely to become distorted by rough handling and which does not require careful packaging to protect it from distortion stresses in handling or shipping.

Objects pertaining to details and economies of the invention will definitely appear from the description to follow. The invention is defined in the claims.

A structure embodying the features of this invention is clearly illustrated in the accompanying drawings, in which:

Fig. 1 is a fragmentary plan view of a mattress embodying the features of my invention, certain of the springs and the mattress covering or upholstery being shown conventionally, and part of the upper frame structure being omitted for clarity of illustration.

Fig. 2 is a plan view of one of the border members embodying my invention in its normal or outwardly bowed form.

Fig. 3 is a fragmentary plan view illustrating steps in the assembling of the border frame to the body springs, certain of the frame structure not germane to the invention being omitted.

Fig. 4 is a fragmentary view in transverse section, the upholstery being illustrated by dotted lines.

Fig. 5 is a fragmentary plan view of a modified form or embodiment of my invention in which a helical tie member is employed for securing the parts together and also showing a modified form of border springs.

Fig. 6 is a fragmentary plan view of a still further modification or embodiment of my invention, the original bowed form of the border member being indicated by dotted lines.

In the mattress embodiment of the invention illustrated I designate the upholstery of the mattress and as this forms no part of my invention it is not illustrated in detail. It is desired to point out, however, that the spring assembly of my invention obviates the necessity for providing special edge packing or stuffing in order to support the upholstery, one of the objects of the invention being to provide a structure which more effectively supports the upholstery at the sides or edges thereof than has heretofore to my knowledge been accomplished.

The spring assembly illustrated in Fig. 1 comprises the rows of body springs 2 connected by helicals indicated at 3, the springs being provided with offsets 4, as shown for instance in the patent to Heuer No. 1,907,541, issued May 9, 1933, receiving the coils of the helicals so that the springs are effectively joined together in the rows. The border springs 5 are preferably of a structure similar to those shown in the said patent to Heuer, comprising flattened coils disposed to present a more effective supporting surface for the mattress upholstery. These springs 5 terminate in the extensions 6 which are connected to the adjacent springs of the rows by means of the helical tie members 3. It will be understood that instead of these helical tie members other suitable connections may be provided.

The border member 7 in the embodiment illustrated is formed of resilient or spring wire and has a plurality of loop-like inwardly disposed offsets 8 of substantial size which, as shown in Fig. 1, are disposed between the end coils of adjacent border springs and secured to certain of the border springs by means of clips 9. The reaches between these clips are secured to the border springs by means of similar clips 10. In Fig. 1 I have shown only one of these border members but it will be understood that there is a similar border member on opposite sides, and in this embodiment they are shown as connected by border end members 11. The border members 7 are preferably initially bowed outwardly as shown in Fig. 2 and when secured to the body springs they are brought into a substantially straight position so that the tendency to return to bowed position exerts an outward pull on the connected springs of the assembly. Since there is an oppositely acting border member on the opposite side of the assembly the two border members act to pull outwardly on the connected rows of springs, maintaining them in upright position and also preventing sagging of the edges of the mattress. It will be noted by reference to

Fig. 4 that in the structure shown the resilient wire border member 7 is employed on only one of the edges of the vertical sides of the mattress or cushion and that on the other edge the end coils of the border springs are connected to one another by the helical 111, thereby constituting an extremely flexible structure which is, however, proof against undue sagging.

In the embodiment of my invention shown in Fig. 5 the border springs 5 have extensions 12 corresponding to the extensions 6 of the embodiment shown in Fig. 1 with the exception that instead of knotting as at 13 in the embodiment of Fig. 1 the extensions 12 of the end coils at the side of the mattress or cushion opposite from the border member 7 terminate in arm-like projections 14 disposed in parallel relation to the flattened external portion of the end coil and engaged by the helical tie member 15 which is threaded or spiraled about said end coil of the border springs and around these arm extensions so that the parts are effectively held in assembled relation.

In the embodiment of my invention shown in Fig. 6 the opposed border members 16 are provided with loop-like offsets 17 which are arranged in overlapping relation to a pair of the body springs 18 and secured thereto by the clips 19, intermediate or reach portions of the border members being secured to the border springs by clips 20.

These border members are outwardly bowed in their original or initial form and are brought into straight position as indicated in Fig. 6. The border members 16 have their end portions 21 terminating in inwardly projecting joint portions 22 connected by the loops or clips 23. The springs are shown conventionally in Fig. 6 but it will be understood that they are in practice connected by suitable means such as the helical tie members 3 best shown in Fig. 4. I have illustrated the border members with the offsets therein at the ends of the assembly but it will be readily understood that this type of border member may be continuous about the spring structure if that is deemed desirable.

Among the advantages which I have obtained is a neat straight border with parts arranged so that there is a tendency to pull out rather than to pull in on the sides of the upholstery. While the border is very flexible under outward stresses or pressures, it readily comes back to position when the pressure or stress is released.

It is common practice to ship mattresses in paper bags or wrappers and as a result many mattresses have been ruined because of the distortion resulting from the mattress being dropped on end in handling. This distorts the border frame members and it is quite impossible to restore the original position in an upholstered structure.

Mattresses embodying my invention are not thus distorted as the loops permit endwise yielding of the border frame under such conditions and they readily return to normal position. It might be said that these loops or offsets serve as shock absorbers for the border members. Further, they will allow substantial distortion of the border members, such as results when the mattress is rolled, without permanently injuring the structure.

The action or tendency of the border members to pull outwardly on the body spring assembly avoids the necessity for using braces, and such braces not only add undesirable rigidity at points

but, unless carefully designed and positioned, they are likely to be felt through the upholstery. The attachment of the offsets of the border members to the body springs maintains the border members in their proper position and prevents any twisting action thereof which might result if the offsets were not attached or supported.

There are various modifications and adaptations of my invention possible other than those I have illustrated, but I believe the disclosure made will enable those skilled in the art to embody or adapt my invention as may be desired.

Having thus described my invention, what I claim as new and desire to secure by Letters Patent is:

1. A spring assembly for mattresses and the like comprising body springs arranged in rows and including border springs having elongated and relatively narrow coils, the end coils of the border springs terminating in inwardly-projecting extensions to which adjacent body springs are connected, and a resilient wire border member connected to the flattened portions of the end coils of the border springs and having a plurality of inwardly-extending loop-like offsets of substantial width therein disposed between adjacent border springs, said offsets being connected by reaches of substantially greater length than the spacing of the arms of the offsets, at least certain of said offsets being connected to the extension of an adjacent border spring, said border member being normally bowed outwardly but being restrained in a substantially straight position through its connections with the said border springs.

2. A spring assembly for mattresses and the like comprising body springs arranged in rows and including border springs having elongated and relatively narrow coils, the end coils of the border springs terminating in inwardly-projecting extensions to which adjacent body springs are connected, and a border member connected to the flattened portions of the end coils of the border springs and having a plurality of inwardly-extending loop-like offsets of substantial width therein disposed between adjacent border springs, said offsets being connected by reaches of substantially greater length than the spacing of the arms of the offsets, at least certain of said offsets being connected to the extension of an adjacent border spring.

3. A spring assembly for mattresses and the like comprising a plurality of rows of body springs, a border frame consisting of a pair of side members having loop-like offsets therein, the offsets being secured to the end coils of at least two springs of a transverse row of springs of the assembly and the portions of the border member between the offsets being secured to the end coils of border springs intermediate those connected to the offsets, said border member portions having end extensions connected to each other and connected to the end border springs of the assembly, said border members being of spring material and normally bowed outwardly so that when secured to the body springs in substantially straight position they act to exert an outward pull on the body springs of the assembly.

4. A spring assembly for mattresses and the like comprising a plurality of rows of body springs, a border frame consisting of a pair of side members having loop-like offsets therein, the offsets being secured to the end coils of at least two springs of a transverse row of springs of

the assembly and the portions of the border member between the offsets being secured to the end coils of border springs intermediate those connected to the offsets, said border member portions having end extensions connected to each other and connected to the end border springs of the assembly.

5. A spring assembly for mattresses and the like comprising a plurality of rows of body springs, a border frame consisting of a side member having loop-like offsets therein, the offsets being secured to the end coils of at least two springs of a transverse row of springs and the portions of the border member between the offsets being secured to the end coils of border springs intermediate those connected to the offsets.

6. A spring assembly for mattresses and the like comprising helically coiled body springs having their end coils connected in transverse rows, and a border frame consisting of oppositely disposed resilient side members having inwardly disposed open loop-like offsets therein, end border members connecting the ends of said side members, said loop-like offsets in the latter being of substantial length and the arms thereof being substantially spaced permitting springing and flexing in the loops and yielding of the border members to endwise thrust thereon, said border members having reaches of substantially greater length than the spacing of said arms connecting said loop-like portions, a plurality of said loops being connected to end coils of adjacent body springs, said resilient side border members being normally bowed outwardly but being restrained in substantially straight position through their connections with the body springs and acting to apply yielding transverse tension to the body springs.

7. A spring assembly for mattresses and the like comprising helically coiled body springs having their end coils connected in transverse rows, and a border frame of resilient wire-like stock comprising oppositely disposed resilient side members connected to one another at the ends thereof by a pair of further border members and having inwardly disposed open loop-like offsets therein, said loop-like offsets being of substantial length and the arms thereof being substantially spaced permitting springing and flexing in the loops and yielding of the side border members to endwise thrust thereon, said offsets being connected by reaches of substan-

tially greater length than the spacing of the arms of the offsets, a plurality of said loops being connected to end coils of adjacent body springs.

5 8. A spring assembly comprising body springs, and resilient border members disposed in opposed relation and connected at their ends, said border members each having a plurality of inwardly disposed loop-like portions therein, said 10 loop-like portions being of substantial length and the arms thereof being substantially spaced, at least certain of said loop-like portions being secured to end coils of adjacent body springs, said border members being bowed outwardly but restrained in substantially straight position through their connections with the body springs, said offset carrying border members having reaches of substantially greater length than the spacing of said arms for connecting said loop-like portions.

9. A spring assembly comprising body springs, and resilient border members disposed in opposed relation and connected at their ends, said border members each having a plurality of inwardly disposed loop-like portions therein, said 25 loop-like portions being of substantial length and the arms of each thereof being substantially spaced, said loop-like portions being connected by reaches of substantially greater length than the spacing of said arms and at least certain of said loop-like portions being secured to end coils of adjacent body springs, said offset carrying border members having reaches of substantially greater length than the spacing of said arms for connecting said loop-like portions.

10. A spring assembly for mattresses and the like comprising a plurality of rows of body springs, and a border frame consisting of opposed members having aligned loop-like offsets therein, and a pair of further border members connected to the ends of said offset carrying members at least certain of said offsets being secured to end coils of certain of the rows of springs, said loops being open and of substantial length and the arms of the loops thereof being substantially spaced permitting springing and flexing and endwise yielding of said opposed border members, said offset carrying border members having reaches of substantially greater length than the spacing of said arms for connecting said loop-like portions.

GEORGE A. STACKHOUSE.
